(57) **CLAIM**

The ornamental design for an applicator for a cerumen collector for an ITE hearing aid, as shown and described.

DESCRIPTION

FIG. 1 is a perspective view of the top, one side and one end of an applicator for the cerumen collector showing my new design.

FIG. 2 is a top view thereof, the bottom view being identical thereto;

FIG. 3 is a side view of said one side, the opposite side being identical thereto;

FIG. 4 is an end view of said one end thereof; and,

FIG. 5 is an end view of the opposite end thereof.
